UNITED STATES PATENT OFFICE

AUGUST OLAF HANSEN, OF NEW YORK, N. Y., ASSIGNOR TO INTERNATIONAL COMBUSTION ENGINEERING CORPORATION, OF NEW YORK, N. Y., A CORPORATION OF DELAWARE

FURNACE

Application filed August 2, 1927. Serial No. 210,056.

My invention relates to furnaces and has special reference to fuel feeding rams for furnaces.

An object of the invention is to provide a 5 novel and improved fuel feeding ram.

Another object of the invention is to provide a device of this character which may be easily controlled to vary the fuel feeding action thereof.

10 The several features of the invention, whereby the above mentioned and other objects may be attained, will be clearly understood from the following description and accompanying drawings, in which:

15 Figure 1 is a side elevation, partly in section, of a portion of a furnace embodying the features of the invention in their preferred form;

Fig. 2 is a sectional plan view on an enlarged scale taken on the line 2—2 of Fig. 1;

Fig. 3 is a sectional view taken on the line 3—3 of Fig. 2;

Fig. 4 is a view corresponding to Fig. 3, but showing parts of the ram in a different position;

Fig. 5 is a transverse sectional view taken on the line 5—5 of Fig. 3; and

Fig. 6 is a detail view in perspective of a component part of the controlling mechanism of the ram.

The furnace illustrated in Fig. 1 of the drawings, is provided with a combustion chamber 2, a fuel hopper 4, a fuel pushing ram 6 for feeding the fuel into the combustion chamber of the furnace, a ram casing 8 having an inlet opening 10 through which fuel from the hopper may pass into the ram casing, and a motor shaft 12 and suitable connections comprising a connecting rod 14, having one end connected with the ram, for reciprocating the ram.

Except as hereinafter described, the parts above referred to may be and preferably are of a well known construction.

45 In accordance with my invention the fuel feeding ram 6 is made in two sections 16 and 18 that extend longitudinally and are arranged one upon the other. The upper section 16 is connected by a wrist pin 20 with the connecting rod 14 so as to be reciprocated

thereby. The two sections of the ram are adapted to be connected and disconnected. When they are connected they reciprocate together, and thus effect the maximum feeding of the fuel. When they are disconnected the lower section is held stationary and serves as a support on which the upper section slides, the feeding of the fuel then being accomplished solely by means of the upper section.

55 The means illustrated in the drawings for connecting and disconnecting the two sections of the ram comprises a latching pawl 22 which is pivotally mounted on a pin 24 secured to the vertical walls of a cored out recess 26 on the under side of the rear portion of the upper section 16. The downward movement of the free end of the pawl 22 is limited by means of a stop lug 28 thereon which engages a lug 30 on the upper ram section 16. When the ram sections 16 and 18 are connected, the 60 tooth 32 of the pawl engages the rear side of a latch block 34 formed on a locking bar 36 which is mounted to slide in a suitable guide-way 38 in the lower ram section 18. The rear portion of the lower ram section 18 is provided with a cored out upwardly opening recess 21 for receiving the pawl 22. The pawl 22 by engagement with the rear side of the latch block 34 causes the lower section of the ram 18 to move with the upper section during 65 the retracting movement of the latter section. The lower section is caused to move with the upper section during the feeding movement thereof, by means of a shoulder 40 on the upper section that engages a shoulder 42 on the lower section. Thus, it will be apparent when the pawl 22 is in locking engagement with the block 34 that the lower ram section will be connected to move with the upper section during both the retracting and fuel feeding movements of the upper section.

70 The ends of the locking bar 36 extend through clearance slots 44 in the ram casing 8 and one end of the bar is provided with a handle 46 by means of which the bar may be 75 pulled outwardly a sufficient distance to withdraw the latch block 34 from beneath the locking pawl 22 whereupon the lower ram section will be disconnected from the upper section. The outward movement of the lock-

ing bar 36 is limited by the engagement of a stop pin 48 on the end of the bar opposite the handle 46 with the corresponding side of the lower ram section 18.

5 To connect the lower ram section 18 with the upper section, the locking bar 36 is pushed inwardly until the inner end of the latch block 34 engages one side wall of the recess 21 which positions the latch block in the path of the 10 free end of the locking pawl 22, whereupon, during the next feeding movement of the upper ram section, the end of the pawl will ride up over an inclined surface 52 on the block 34 so as to permit the tooth on the pawl 15 to drop down into latching position over the rear side of the block.

It may be noted that the locking bar 36 may be shifted longitudinally to connect and disconnect the two ram sections during the 20 fuel feeding movement of the upper section. Also, that the engagement of the cooperating shoulders 40 and 42 during said movement of the upper section will advance the lower section to its innermost position which is directly beneath the inlet opening 10 in the ram casing. The lower section is held from further inward movement by the engagement of the ends of the locking bar 36 with the rear end walls of the slots 44 through which they 30 extend. With the lower section thus positioned all of the fuel thereafter entering the ram casing will drop down upon the top surface of the lower section and be fed into the furnace by the upper section.

35 With this construction it will be apparent, for a given speed of the driving mechanism of the fuel pushing ram that with the lower section connected to the upper section, the fuel displacement of the combined plunger 40 area is available for pushing in the maximum quantity of fuel, and also when the lower section is disconnected from the upper section it maintains its position at the inward end of its stroke and the upper section functions alone to feed the fuel into the furnace. Thus, an extremely simple device is provided 45 which may be easily controlled by the operator to vary the amount of fuel fed into the combustion chamber of the furnace to meet 50 different conditions.

The ram casing is provided with openings 54, and the lower wall of the upwardly opening recess 21 of the lower ram section is provided with an opening 56 which is located directly beneath the free end of the latching pawl 22 when the pawl is in locking position. The opening 56 is adapted to register with the openings 54 when the lower section is in either its extreme inward or retracted positions so as to permit access to be had to the free end of the pawl.

As will be evident to those skilled in the art my invention permits various modifications without departing from the spirit 60 thereof or the scope of the appended claims.

What I claim is:

1. A fuel feeding ram for a furnace having, two fuel pushing sections relatively movable longitudinally, means for longitudinally reciprocating one of said sections with relation to the other to feed the fuel, and means under the control of the operator for operatively connecting the other ram section to and disconnecting it from the first mentioned section. 70

2. A fuel feeding ram for a furnace having, two fuel pushing sections relatively movable longitudinally, and means under the control of the operator to either reciprocate longitudinally both of said sections together 80 or to reciprocate longitudinally one of said sections while the other is held stationary. 75

3. A fuel feeding ram for a furnace having, two fuel pushing sections arranged one above the other and relatively movable longitudinally, means for longitudinally reciprocating the upper section with relation to the lower to feed the fuel, and means under the control of the operator for operatively connecting the lower section to and disconnecting it from the upper section. 85 90

4. A fuel feeding ram for a furnace having, two fuel pushing sections arranged one above the other and relatively movable longitudinally, means for longitudinally reciprocating the upper section with relation to the lower section to feed the fuel, and means adapted to be controlled by the operator for operatively connecting the lower section to and disconnecting it from the upper section when the sections are substantially at the 95 limit of their fuel feeding movement. 100

5. A fuel feeding ram for feeding fuel into a furnace having, two fuel pushing sections arranged one above the other and relatively movable longitudinally, means for longitudinally reciprocating the upper section with relation to the lower to feed the fuel into the furnace, cooperating shoulders on said sections adapted to engage during the fuel feeding movement of the upper section to cause said sections to move together during said movement, and a ratchet device adapted to be thrown into and out of operation by the operator to operatively connect the lower section to the upper section to cause the lower section to move with the upper section during the retracting movement of the latter. 105 110 115

6. A fuel feeding ram for feeding fuel into a furnace, having two fuel pushing sections arranged one above the other and relatively movable longitudinally, means for longitudinally reciprocating the upper one of said sections with relation to the other to feed the fuel into the furnace, and means under the control of the operator during the operation of the upper section for operatively connecting the lower section to and disconnecting it from the upper section. 120 125

7. A fuel feeding ram for feeding fuel

from a hopper into a furnace in which the ram casing is provided with an inlet opening for permitting fuel to pass from the hopper into said casing, having two fuel pushing sections arranged one above the other and relatively movable longitudinally, means for longitudinally reciprocating the upper section with relation to the lower section to feed the fuel into the furnace, and means for operatively connecting the lower ram section to and disconnecting it from the upper ram section, the two sections when at the limit of their fuel feeding movement being positioned directly beneath said opening in the ram casing, and the lower section being maintained in this position when disconnected.

8. A fuel feeding ram for feeding fuel into a furnace having two fuel feeding sections relatively movable longitudinally, means for longitudinally reciprocating one of said sections with relation to the other to feed the fuel into the furnace, and means under the control of the operator during the operation of said reciprocating section for operatively connecting thereto and disconnecting therefrom the other section.

In testimony whereof, I have signed my name to this specification this 29th day of July, 1927.

30 AUGUST OLAF HANSEN.
